UNITED STATES PATENT OFFICE.

GEORGE MIDDLEMAN, OF PHILADELPHIA, PENNSYLVANIA.

DESIGN FOR A COMBINED PHONOGRAPH AND RADIO CABINET.

Application filed April 7, 1925. Serial No. 13,046. Term of patent 7 years.

To all whom it may concern:

Be it known that I, GEORGE MIDDLEMAN, a citizen of the United States, residing at Philadelphia, in the county of Philadelphia and State of Pennsylvania, have invented a new, original, and ornamental Design for a Combined Phonograph and Radio Cabinet, of which the following is a specification, reference being had to the accompanying drawing, forming part thereof.

The figure is an isometric view of a combined phonograph and radio cabinet, illustrating my new design.

I claim:

The ornamental design for a combined phonograph and radio cabinet, as shown.

GEORGE MIDDLEMAN.
